RUNWAY MARKER

Irvin L. Valley, 1550 Narrows Drive,
Tacoma, Wash. 98406

Filed Mar. 17, 1969, Ser. No. 16,267

Term of patent 14 years

Int. Cl. D29—99

U.S. Cl. D72—1

FIG. 1

FIG. 2

FIG. 3

FIG. 4

FIG. 1 is a perspective view of a runway marker showing a first form of my new design;

FIG. 2 is a perspective view of another form of my runway marker;

FIG. 3 is a perspective view of still another form of my runway marker; and

FIG. 4 is a plan view of the marker of FIG. 3.

In each form of the invention, the top surface of the marker is reflective and the two cross bands over the top surface at opposite ends of the marker are also reflective but of different color than the intermediate top surface area. In the embodiment of FIG. 3, the longitudinal bands are still of different color than the other two colors. It is understood that the contrasting colors are not limited to those specifically indicated in the drawing disclosure.

I claim:

The ornamental design for a runway marker, as shown and described.
